TREATING HYDROCARBONS

Jackson R. Schonberg, Westfield, and Harold J. Moyer, Summit, N. J., assignors to Standard Oil Development Company, a corporation of Delaware

Application December 27, 1940, Serial No. 371,898

3 Claims. (Cl. 196—52)

The present invention relates to improvements in the art of treating hydrocarbons, and, more particularly, to the art of preparing or conditioning a feed stock for a catalytic cracking operation so that when the stock is cracked catalytically it will produce greater yields of gasoline of high anti-knock quality, without forming excessive amounts of coke, and be otherwise more desirable for catalytic cracking than would be possible without benefit of methods herein disclosed.

It has long been known that a cracking stock comprising mostly paraffinic hydrocarbons is the most desirable one to subject to thermal cracking to produce high yields of gasoline while at the same time maintaining satisfactory operating conditions, and without excessive formation of undesirable by-products such as gas and coke. It is known further, that as the paraffinicity of cracking stocks decreases the yields of gasoline attainable by thermal cracking also decrease, while the undesirable products of decomposition and the severity of operating conditions to obtain decomposition are relatively increased.

In the catalytic cracking of petroleum oils, however, it has been found that stocks of the highest content of paraffinic hydrocarbons are not the most desirable when judged by gasoline yields, relative production of the undesirable products, and conditions of operation.

We have discovered that better yields of high quality gasoline can be secured from catalytic feed stocks in which the degree of unsaturation and cyclization is—or has been caused to be—high, than from stocks in which paraffinic hydrocarbons predominate.

Since gas oils which are basic materials for cracking operations vary widely in their hydrocarbon composition due both to origin and boiling range, the desirability of conditioning a specific stock for catalytic cracking in the manner we propose is dependent on its composition. That is, if a virgin stock is predominantly paraffinic, it is less susceptible to catalytic cracking reactions than a stock predominantly naphthenic, and should be conditioned in a manner to remove or convert paraffins, or conversely, to increase the concentration of olefinic and naphthenic hydrocarbons, in order to improve the catalytic cracking yields and operation. If, however, the stock to be catalytically cracked is largely naphthenic in character, then the proposed conditioning is not economical or advisable.

The object of our invention is to reduce the paraffinicity of such petroleum fractions as are predominantly paraffinic in character, by means of thermal cracking and other pyrolytic decomposition such as coking of petroleum residues, for the purpose of preparing and selecting a gas oil charge stock for catalytic cracking which is more

susceptible to the catalytic reactions and consequently produces greater yields of high octane gasoline than could be obtained without thermal conditioning.

In such thermal pretreatment we do not subject the oil fraction to intensive pyrolysis. In fact, severe thermal cracking is avoided in order to minimize the production of gasoline and gaseous hydrocarbons. The object of the pretreatment is primarily that of reducing paraffinic hydrocarbons to naphthenes and olefins, and for this purpose advantage is taken of the greater reactivity of paraffins to decompose under thermal conditions than are the hydrocarbons of other types.

The thermal pretreatment is applicable to gas oils, reduced crude oils and crude pitch residues. Such products as crude pitch, high-boiling cracked tar and other petroleum residues may also be coked. In both of these pyrolytic processes, the gas oil product is then subjected to catalytic cracking. This procedure differs from present methods of cracking wherein the products of distillation of the crude oil, without cracking, are subjected directly to the catalytic cracking reactions.

The principle embodied in our invention is not limited to use on gas oils or other stocks of high-boiling character. It can be applied also to the cracking of gasoline fractions, when it is desirous to improve the octane number of this product. The gasoline to be improved in octane number is first mildly reformed pyrolytically, after which the resulting liquid product is subjected to further reforming catalytically to the quality desired.

In order to illustrate our invention more fully but without placing a limitation thereon, the following specific example is set forth in connection with the accompanying drawing, which shows diagrammatically an apparatus in which the present invention may be carried into effect.

Referring in detail to the drawing, a South Sumatran reduced crude having the following inspection

45	Gravity, °A. P. I.	21.5
	Initial boiling point—°F.	454
50	5% at, °F.	725
	10% at, °F.	760
55	20% at, °F.	815
	30% at, °F.	847
60	40% at, °F.	875
	Per cent off at 900° F.	48
	Sulfur	% 0.15
	Furol viscosity at 140° F.	26.1

is introduced into the system through line 1 and thence discharged into a coil 3 disposed in a furnace setting 4, in which coil it is heated to a temperature of 870° F. and thereafter withdrawn through line 6 and discharged into a drum reactor

8 where the average temperature is 831° F., the oil feed rate to the drum being 2.6 volumes of oil per volume of reactor per hour. A pressure of 200 lbs./square inch gauge is maintained in drum 8 during reaction. The oil remains resident in the said drum under the conditions stated for a period of about two minutes and then is withdrawn through line 10 and discharged into a fractionating column 12. In fractionating column 12, the following fractions are removed: Through line 14 13.7 volume per cent based on the original charging oil of 400° F. final boiling point gasoline, and 2.7 by weight per cent of normally gaseous hydrocarbons are withdrawn. About 65 volume per cent of gas oil having an A. P. I. gravity of 28.1° is withdrawn from tower 12 through line 18. From the bottom of tower 12, through line 16 21.4 volume per cent of pitch bottoms, having an A. P. I. gravity of 4.8° are withdrawn. In drum 8 0.9 per cent by weight of coke is formed as a result of the pyrolysis which takes place.

The pitch bottoms or tar withdrawn through line 16 are fed to a continuously operated coking drum 19. The pitch bottoms in the run, as stated, have an A. P. I. gravity of 4.8°, a furol viscosity of 225.5 at 210° F., a sulfur percentage by weight of 0.18, a softening point of 123° F., and a Conradson carbon content of 23.8%. This material was, after preheating in furnace 17, continuously fed to the coking drum 19 where it was subjected to the following operating conditions; namely, an inlet temperature of 885° F., and an outlet temperature of 788° F., a pressure of 50 lbs./sq. in. gauge being maintained in the drum or by other suitable means. The reaction products were withdrawn from drum 19 through line 31 and discharged into a fractionating column 33. From fractionating column 33 5.5 per cent by weight of normally gaseous hydrocarbons, and 12.8 per cent by volume of 400° F. end point gasoline were withdrawn overhead through line 35, 55.5 per cent by volume of gas oil having an A. P. I. gravity of 20.1° was withdrawn from the column 33 through line 36, and this material was discharged into line 18 where it mixed with the gas oil obtained from fractionating column 12. The mixed fraction fed to coil 20 had the following inspection:

Gravity, ° A. P. I.	26.9
Initial boiling point, ° F.	440
50% off at, ° F.	750
90% off at, ° F.	920
Aniline point, ° F.	185

This material was heated in coil 20 of furnace 21 to a temperature of 906° F., whereupon it was withdrawn from the coil and mixed with a powdered catalyst in an injection means 22 or other suitable mixing device, the amount of catalyst being 2.14 parts by weight of catalyst to 1 part by weight of oil. The catalyst may be an acid treated clay, and preferably in powdered form, having a particle size within the range of from 200-400 mesh. The catalyst may be stored in a receptacle 25 from which it may be withdrawn through transfer line 27 and discharged into injection means 22, as indicated. The suspension of catalyst in the oil vapors is then withdrawn from injection means 22 through line 24 and discharged into the bottom of a reaction chamber 28 where, under the conditions stated, the vapors remain for a period of 10.8 seconds, and under a pressure of about 30 lbs./sq. in. gauge. In reactor 28 the gas oil undergoes conversion forming

40 per cent by volume of gasoline having a final boiling point of 400° F. The reaction vapors are withdrawn through reactor 28 through line 28 and discharged into a second fractionating column 30. From fractionating column 30 5.5 per cent by weight of dry gas and 4.6 per cent by volume of butane, and 40 per cent by volume of gasoline were withdrawn overhead through line 40; 4.5 per cent by weight of coke was deposited on the catalyst in reaction chamber 28. Fifty-two per cent by volume of gas oil was withdrawn from fractionator 30 through line 42, this gas oil having an A. P. I. gravity of 24°. This gas oil fraction was discharged into a furnace 45 in a coil 46 in which it was heated to reaction conditions as will subsequently appear. The material in line 42 had the following inspection:

Gravity, ° A. P. I.	24.0
Initial boiling point, ° F.	442
50% off at, ° F.	710
Final boiling point, ° F.	900

This material was heated in coil 46 to a temperature of 1000° F., while being maintained under a pressure of 750 lbs./sq. in. gauge, the feed rate of oil to the reaction coil being 41.7 volumes of oil per volume of reactor per hour. In this coil the reaction products formed were discharged into line 50 and thereafter discharged into a fractionator 52. From fractionator 52 8.4 per cent by weight of dry gas and 28 per cent by volume of 400° F. end point gasoline were withdrawn overhead through line 55; 63.8 per cent of tarry material having an A. P. I. gravity of 12° was withdrawn through line 57; 1.0 per cent by weight of coke was also produced in the reaction.

The specific example hereinbefore set forth is purely illustrative and does not constitute a limitation on our invention.

40 A variation of the procedure hereinabove set forth may be desirable when an examination of the thermally conditioned gas oil reveals experimentally that its several parts, obtained by distillation and separated according to boiling range, 45 vary widely with respect to types of hydrocarbons composing each. Those fractions of the gas oil which contain mainly naphthenic, olefinic and aromatic hydrocarbons are preferably next subjected to catalytic cracking, while those predominantly paraffinic are recycled to the thermal conditioning operation. To make such separation by boiling range, suitable fractionation can be applied to the thermally cracked gas oils as produced.

Depending of course on the nature of the 55 original charging stock, the operating conditions in both thermal and catalytic cracking will vary. The gist of our invention, however, resides in the concept of first thermally treating or conditioning a charging stock in order to prepare a gas oil which will be suitable for catalytic cracking and recovering from the catalytic cracking operation a gas oil which is also thermally treated in order to condition or prepare it for further catalytic cracking. In the thermal cracking operation hereinbefore set forth, the operating conditions may vary within the range of from about 825° F.-1000° F., or higher if steam is employed. The pressure conditions may vary from atmospheric to 1000 lbs./sq. in. gauge. In the catalytic cracking operation, the temperatures may vary from 825° F.-925° F., and the pressures from 0 lbs./sq. in. gauge to 45 lbs./sq. in. gauge, although preferably the pressure in this phase of the process 75 is in the neighborhood of 15 lbs./sq. in. gauge.

What we claim is:

1. The method of cracking which comprises subjecting a paraffin base hydrocarbon oil containing fractions of the gas oil boiling range to a thermal treatment at temperatures ranging from about 825° to about 1000° F., pressures ranging from atmospheric to 1000 lbs./sq. in. and for times of the order of 2 minutes, the exact conditions of temperature pressure and treating time being adapted to the specific composition of said oil so as to cause an increase of the naphthenicity of said oil without the formation of substantial amounts of cracked gasoline and gaseous hydrocarbons; recovering from the thermally treated products mostly a gas oil fraction of increased naphthenicity derived from paraffinic hydrocarbons; and subjecting said recovered gas oil fraction to catalytic cracking.

2. The method of cracking which comprises passing a reduced paraffin base crude oil containing fractions boiling in the gas oil range through a heating coil until the oil reaches a temperature of the order of 800 to 950° F., subjecting the pre-heated oil in a drum reactor to a thermal treatment at an average temperature in the range of 825 to 925° F., a pressure in the range of 0 to 200 lbs./sq. in. and for a time of the order of two minutes to increase the amount of naphthenes

in said oil, recovering from the products thus obtained mostly a gas oil fraction of increased naphthenicity derived from paraffinic hydrocarbons and subjecting said recovered gas oil fraction to catalytic cracking.

3. The method of cracking which comprises passing a reduced paraffin base crude oil containing fractions boiling in the gas oil range through a heating coil until the oil reaches a temperature of the order of 800 to 950° F., subjecting the pre-heated oil in a drum reactor to a thermal treatment at an average temperature in the range of 825 to 925° F., a pressure in the range of 0 to 200 lbs./sq. in. and for a time of the order of two minutes to increase the amount of naphthenes, recovering from the products thus obtained mostly a gas oil fraction of increased naphthenicity derived from paraffinic hydrocarbons and subjecting said recovered gas oil fraction to catalytic cracking with an acid treated clay catalyst at a temperature in the range of 825 to 975° F. and under a pressure of 0 lbs./sq. in. gauge to 45 lbs./sq. in. gauge to obtain a high yield of gasoline, and fractionating the catalytic cracking products separately from the thermal cracking products.

JACKSON R. SCHONBERG.
HAROLD J. MOYER.
